UNITED STATES PATENT OFFICE.

FRIEDRICH LUTZ, OF STUTTGART, GERMANY, ASSIGNOR TO UNION SPECIAL MASCHINENFABRIK, G. M. B. H., OF STUTTGART, GERMANY.

NEEDLE-ACTUATING MECHANISM FOR SEWING MACHINES.

Application filed June 6, 1927, Serial No. 196,966, and in Germany June 23, 1926.

The invention relates to new and useful improvements in needle actuating mechanisms for sewing machines, and more particularly to the means for supporting the 5 needle lever which imparts reciprocations to the needle bar carrying the needle or needles.

An object of the invention is to provide a needle lever supporting means wherein the needle lever is provided with a fulcrum 10 support at both sides of the needle lever, and wherein the supporting stud for the needle lever is provided with tapered bearings capable of endwise adjustment in the supporting bushings therefor for taking up wear. 15 A further object of the invention is to provide a needle lever supporting means of the above type, wherein the needle lever is capable of lateral adjustment on the supporting shaft or stud therefor, so that the needle lever may be lined up relative to the needle bar which is reciprocated thereby.

In the drawings—

Figure 1 is a front view of a machine embodying the improvements, and 25 Fig. 2 is a sectional view on the line A—B of Fig. 1.

The invention has to do with a needle lever which imparts reciprocation to the needle bar. The invention is directed to the 30 means for supporting the needle lever and also to the means for shifting the needle lever on its support for lining up the needle lever relative to the needle bar. The needle lever is rigidly attached to a shaft or 35 stud which is provided with tapered bearing sections, one at each side of the needle lever. The needle lever is mounted within the frame or housing of the sewing machine, and these tapered bearings are journaled in 40 bushings carried by the frame. Means is provided whereby the stud or shaft supporting the needle lever is capable of endwise adjustment relative to the frame for taking up the wear on the bearings. The needle lever is attached to the supporting stud or 45 shaft so that it may be adjusted endwise thereof for lining up the needle lever relative to the needle bar.

Referring more in detail to the drawings, 50 the invention is shown as applied to a sewing machine including a supporting bed and an overhanging arm, at the outer end of which the needle bar *b* reciprocates. Mounted on the needle bar is a needle *a*. The needle bar is reciprocated by a lever *d* which

is connected to the needle bar by a link *c*. The lever *d* is located within the frame of the sewing machine and is oscillated or vibrated therein by an eccentric strap *g* cooperating with an eccentric *f* on the main 60 shaft *e*. The needle lever *d* is mounted on a shaft or stud *h*. The needle lever is formed with a hub through which the shaft or stud passes, and the needle lever is rigidly secured to the stud or shaft *h* by screws *o*, *o*. 65 This shaft or stud *h* is provided with tapered bearing sections *k*, *k*, one at each side of the needle lever *d* and tapering in the same direction. The frame of the machine is formed with bosses *i*, *i* which are bored to receive 70 bushings, and the tapered bearings are mounted in the bushings carried by the frame. A collar *n* is placed on one end of the shaft outside of the frame, and a collar *n'* placed on the other end of the shaft outside of the frame. Nuts *m*, *m'* are threaded 75 on to the respective ends *l*, *l'* of the shaft. They may be set in any desired position on this shaft or stud which supports the needle bar. By loosening the nuts *m'* and turning up on the nuts *m*, the shaft may be moved endwise in the frame, and the bushings therefor for taking up the wear in the bearing. By loosening the screws *o*, *o*, the 80 needle lever may be shifted on the shaft or stud carrying the same for the purpose of lining up the lever with the needle bar.

It is obvious that minor changes in the details of construction may be made without departing from the spirit of the invention as set forth in the appended claims.

Having thus described the invention, what I claim as new and desire to secure by Letters Patent, is—

1. A sewing machine including a frame, a needle bar, a needle carried thereby, a needle lever within the frame for reciprocating said needle bar, a shaft to which said needle lever is attached, said shaft having bearing sections tapering in the same direction, means carried by said frame at the opposite sides of said lever for supporting the respective tapered bearings whereby the shaft may freely oscillate, means whereby said shaft may be adjusted in the frame for taking up the wear in the bearings, and means whereby said needle lever may be adjusted endwise of the shaft for positioning the same in the frame.

2. A sewing machine including a frame,

a needle bar, a needle carried thereby, a needle lever within the frame for reciprocating said needle bar, a shaft to which the needle lever is attached, said shaft having 5 the ends thereof threaded, said shaft being also provided with bearing sections tapering in the same direction, means carried by said frame at the opposite sides of said lever for supporting the respective tapered bearings 10 whereby the shaft may freely oscillate, collars on the ends of said shaft adapted to engage the outer faces, respectively, of the frame, nuts threaded on to the ends of the shaft for holding the shaft in position and 15 permitting endwise adjustment thereof, and means whereby the needle lever may be adjusted endwise of the shaft for positioning the same in the frame and alining the needle lever with the needle bar.

20 3. A sewing machine including a frame,

a needle bar, a needle carried thereby, a needle lever within the frame for reciprocating the needle bar, a shaft to which said needle lever is attached, said shaft having bearing sections tapering in the same direction, one of which is smaller in its maximum diameter than the other in its minimum diameter, bushings carried by said frame at the opposite sides of said lever and shaped 25 for receiving and supporting the respective 30 tapered bearings whereby the shaft may freely oscillate in said bushings, means for securing said shaft in said bushings and for adjusting the same endwise to take up wear, and means whereby the needle lever may be 35 adjusted endwise of the shaft for alining the same with the needle bar.

In testimony whereof, I affix my signature.

FRIEDRICH LUTZ.
